UNITED STATES PATENT OFFICE.

DECATUR S. McDANNELL, JR., OF MOLINE, ILLINOIS.

DESIGN FOR A SIGN-POST.

52,751.

Specification for Design.

Patented Dec. 10, 1918.

Application filed September 12, 1918. Serial No. 253,831. Term of patent 7 years.

To all whom it may concern:

Be it known that I, DECATUR S. McDANNELL, Jr., a citizen of the United States, residing at Moline, in the county of Rock Island and State of Illinois, have invented a new, original and ornamental Design for a Sign-Post, of which the following is a specification, reference being had to the accompanying drawing, forming part thereof.

The figure is an elevation of a sign post, showing my design.

I claim:

The design for a sign post as shown.

DECATUR S. McDANNELL, JR.
